UNITED STATES PATENT OFFICE.

FITZ GERALD SHELBY AND PERRY OLMSTED, OF LOS ANGELES, CALIFORNIA.

COMPUTING FOLDING SQUARE.

1,238,833.

Specification of Letters Patent.

Patented Sept. 4, 1917.

Application filed February 15, 1915. Serial No. 8,429.

To all whom it may concern:

Be it known that we, FITZ GERALD SHELBY and PERRY OLMSTED, citizens of the United States, and residents, respectively, of Los Angeles, in the county of Los Angeles and State of California, and Los Angeles, in the county of Los Angeles and State of California, have invented a certain new and useful Improvement in Computing Folding Squares, of which the following is a full, clear, and exact description.

This invention relates to a computing folding square, and is an improvement over a somewhat similar device constituting the subject matter of our prior application, Serial #826,567, filed March 23rd, 1914, and entitled Folding combination pocket square.

In our prior application above referred to, we have disclosed a folding square capable of being used in numerous ways or for a variety of purposes such as for marking, gaging, etc. The instrument as disclosed in said application includes a body or so-called beam having certain linear and angular scale graduations and provided with a marking device carried by a blade, which at one end has a sliding connection with the body and is connected midway between its ends to the body by means of a pivoted link which causes the marker or marking element at the outer end of the blade to move in a line at right angles to the body when the blade is moved inwardly toward the body or outwardly therefrom.

The present invention has for its main object to improve the efficiency and field of use of the instrument by providing certain improvements which enables it to perform in a more satisfactory manner the functions described in the prior application, and to permit it to be used for a variety of other purposes.

One of the principal features of the present invention resides in the extensible support for the marking device, this support in accordance with the present invention being a lazy-tong construction, the parts or elements of which not only enable the marking device to have a range of movement greater than that in our prior instrument, but also constitute marking or ruling and measuring elements which coöperate in a manner hereinafter described with certain other elements of the instrument such as the various special scales or graduations provided on the face of the body of the tool and the sliding indi-

cator connected to one arm of the marker support.

Our invention may be further briefly summarized as consisting in certain novel details of construction and combinations and arrangements of parts which will be described in the specification and set forth in the appended claims.

In the accompanying sheet of drawings wherein we have shown the preferred embodiment of our invention, Figure 1 is a top plan view of the square in folded or collapsed condition; Fig. 2 is a rear view of the same; Fig. 3 is a top plan view with the top plate of the body removed; Fig. 4 is an end view looking toward the left of Fig. 1; Fig. 5 is an end view looking toward the right of Fig. 1; Fig. 6 is a transverse sectional view substantially along the line 6—6 of Fig. 1; Fig. 7 is a transverse sectional view substantially along the line 7—7 of Fig. 1; Fig. 8 is a detail plan view of the sliding block to which one of the arms of the marker support is pivoted, and of the indicator carried by the block; Fig. 9 is an edge view of the square looking toward what may be termed the rear edge; Fig. 10 is an edge view looking toward what may be termed the front edge, the tool here being shown inverted; Fig. 11 is a plan view similar to Fig. 1 showing the extension slide, some of the different positions in which this slide may be placed being shown by full and dotted lines; Figs. 12, 13 and 14 are views of the instrument showing some of the important uses or functions of the same; Fig. 12 showing the instrument when used as a square or as a gage; Fig. 13 showing the instrument when used for determining the bisecting angle of a corner; and Fig. 14 showing the instrument when used as a clinometer.

Referring now to the drawings, it will be seen that the instrument or folding square includes a flat rectangular-shaped body or so-called beam composed of upper and lower metal plates 10 and 11 which are securely fastened together and are spaced a slight distance apart. A rib or ridge 12 extending substantially the length of the body divides the space between the plates into two parts, one of which is adapted to receive an extension slide to be referred to presently, and the other of which is adapted to receive the collapsed or folded marker support. This body or beam is provided with straight parallel edges, and in order that it may be used

as an ordinary scale or ruler, it is provided along one edge of the top plate 10 with ordinary scale or measuring graduations 13. The top plate is provided also with numerous other special graduations which coöperate with an indicator to be referred to presently.

On the lower side of the body is a flange 14 located a short distance inwardly from the front edge of the body. The front face of this flange constitutes a shoulder adapted to bear against the edge of a board or other object on which the marking or measuring is to be done. This flange, the side faces of which extend nearly the length of the body or beam and parallel to the edges thereof, is very important in the use of the instrument, for without the flange it would be practically impossible to obtain accurate results.

The top plate 10 is provided with a slot 15 which extends nearly the length of the body in a direction parallel to the side edges thereof. This slot receives a slide block 16 which is adapted to be moved freely along the slot, but may be clamped in any position along the slot, by means of a clamping set screw 16^a. This block carries a movable indicator in the form of a beveled cross piece 17 adapted to coöperate with several sets of scales or graduations.

The marker previously referred to is in this instance carried by a lazy-tong extensible support which is movable inwardly and outwardly with respect to the body or beam, and when folded or collapsed lies between the upper and lower plates or in the slot on one side of the dividing rib 12, as shown in Fig. 1. The upper corner of the body is notched or cut away, as shown at 18, in order that the extensible support may be compactly folded between the plates of the body and in order that the point of the marker may be moved from and to a position substantially in line with the front face of the flange 14, so that a line may be drawn by the marker from the very edge of the board against which the square is placed. This extensible marker support is composed of two inner members 19 and 20 and two outer members 21 and 22 which are pivoted together by means of pins or rivets so as to form a lazy-tong construction. One end of the arm 19 is pivotally connected to the body or beam at 23 in line with the slot 15, and the inner end of the arm 20 is pivotally connected to the sliding block 16 in line with the pivotal point 23. Furthermore, the arm 19 and the arm 20 are of precisely the same length and are pivoted together at a point 24 midway between their ends; the arm 21 which is pivoted at 25 to the outer end of arm 19 is of precisely the same length as the arms 19 and 20, and the arm 22 which is half the length of the other arms has one

end pivoted at 26 to the outer end of the arm 20 and at its other end is pivoted to the arm 21 at a point 27 midway between the ends of arm 21. At the outer free end of the arm 21 is a marker 30 which may be of any suitable construction, but in this case consists of a marker proper 30^a (see particularly Fig. 10), which is preferably a piece of lead or other suitable marking material carried by a shank of a screw 30^b adapted to be screwed into a threaded socket of a small cylindrical member 30^c secured at the outer end of the arm 21. It will be observed that by reason of this construction as the lazy-tong support is extended the sliding block will move along the slot toward the pivotal axis of arm 19, and as the support is collapsed the sliding block will move in an opposite direction. It will be observed also that as the support is either extended or moved inwardly toward the body the marker moves in a straight line at right angles to the body or beam, and if the square is placed along the edge of the board 32, as in Fig. 12, and the support is moved outwardly, the marker will draw a line such as indicated at 31 in Fig. 12 at right angles to the edge of the board designated 32. In other words, the instrument when used in this manner serves as an ordinary carpenter's square.

The instrument may be used as a panel gage and in the use of the instrument for this purpose the sliding block 16 will be clamped in position when the marker has been moved outwardly the proper distance from the edge of the flange 14, so that when the square is placed against the edge of a board and is moved along such edge the marker will draw a line such as shown at 34 in Fig. 12 at 105 the desired distance from the edge of the board and parallel thereto. In order that the instrument may be conveniently used as a panel gage, the upper plate 10 of the body or beam is provided with a series of graduations 35 which are preferably marked in terms of inches to indicate different panel widths measured outwardly from the face of the flange 14, these graduations being in the second column from the right hand edge 115 of the plate, as shown at Fig. 1, this column being indicated on the face of the plate "Panel gage." Any desired width of panel can be obtained by setting the sliding block with the edge of the indicator 17 on the 120 graduation corresponding to the gage desired.

Not only do the arms 19 to 22 form the extensible support for the marker, but they are used for ruling or marking purposes, that is 125 for marking lines at any desired angles with respect to the edge of the board, the inner arms 19 and 20 being particularly useful for this purpose, although the arms 22 and 21 are parallel, respectively, to the arms 19 and 130

20, and make the same angles with respect to the edge of the board against which the square is placed as do the arms 19 and 20. In order that the ruling arms 19 and 20 may be shifted to and set at any desired or predetermined angle, the upper plate 10 of the ruler body or beam is provided with a scale 36 graduated in degrees, the different graduations indicating the different angles which the arms 19 and 20, etc., make with respect to the edge of flange 14 or the edge of the board against which the square is placed, this scale 36 being in the third column from the left hand edge or rear edge 15 of the body or beam, as shown in Fig. 1.

When the edge of the indicator is placed on the 45° graduation of the scale, the square may be used as a miter square for the arms 19 and 20 are then at angles of 45° to the face or edge of the flange 14. When these arms are in the position stated, that is, in the miter gage position, the arm 22 and the outer part of the arm 21 are thence at right angles to each other, and these parts thence 25 constitute a trisquare and may be used for that purpose.

Not only does this scale 36 enable lines to be drawn on a board along the arms 19 and 20 at any desired angles, but by means of 30 this scale the instrument may be used as a protractor to determine the angle in degrees made of any two lines, for by adjusting the lazy-tong construction until the edge of arm 19 or 20 and the adjacent edge of 35 the body or beam of the square make the same angle as or coincide with the lines of an unknown angle, the position of the indicator will indicate on the scale 36 the particular angle which these lines make.

40 We will next describe one of the most important uses or functions of the instrument, namely, that of a rafter gage or protractor, the instrument as improved by us being particularly adapted for marking the lines of 45 cut on all rafters which enter into a building construction, and this use as a rafter gage being due to the provision of several sets of rafter graduations with which the indicator coöperates. For example, in column marked 50 37, we have provided a set of graduations by which the plumb cut of common rafters may be determined, these graduations being in terms of vertical rise per horizontal foot length. The carpenter knowing the inclination which the roof of the building is to 55 have in terms of inches rise per horizontal foot has only to set the indicator 17 on the scale 37 at a point corresponding to the rise of the roof, and when this is done the arm 60 19 or arm 20 is in the proper position to give the line of plumb cut when the square is placed against a rafter. The line can be drawn along either the arm 19 or arm 20 depending upon which side of the rafter the 65 square is placed. At the lower part of this

same column 37 there is a second scale 38 by which the line of the heel cut of common rafters may be determined. Additionally, there are other scales from which all other necessary rafter cuts can be obtained, these 70 scales including a scale 39 by which the line of plumb cut for hip or valley rafters may be determined, a scale 40 in the same column with the scale 39 by which the line of heel cut of the hip or valley rafters may be determined, a scale 41 by which the line of side cut for hip or valley rafters may be determined, a scale 42 by which the line of side cut of jack rafters may be determined, and also a column 43 by which 75 the line of cut of sheathing may be determined to cause the sheathing which is nailed to the rafters to make the proper angles over the hip or valley rafters. All these scales 37 to 43 are preferably graduated in terms 80 of inches rise per horizontal foot, so that regardless of the particular rafter being cut, whether the same is a common rafter, hip or valley rafter, jack rafter, or whether the cut is for the top or heel of the rafter, 85 the angle of cut can be determined, and thence marked on the rafter by simply adjusting the slide or block until the edge of the indicator is opposite the particular graduation of a scale corresponding to the known 90 roof inclination. It is thus possible with this instrument to easily and accurately determine all the necessary rafter cuts which heretofore have required a great deal of calculating and several instruments for their 95 determination.

100 Additionally, we have provided a special scale in column marked 44 by which we are enabled to obtain by the simple setting of the indicator, miters of polygon of numerous 105 different numbers of sides, the scale here shown having graduations to any of which the indicator may be set, to determine the miter of any polygon from a 5-sided polygon or pentagon to a 12-sided polygon or 110 dodecagon. The carpenter or user of the instrument knowing the desired polygon has simply to set the indicator to the graduation marked 5^s, 6^s or whatever the number of sides may be, and when the sliding block is 115 clamped with the indicator in the proper position the arms 19 and 20 will be in the position relative to the edge of flange 14 corresponding to the line of cut for that 120 particular polygon.

125 The instrument may also be used to advantage in determining the bisecting angle of a corner, and the manner in which the instrument is used for this purpose is illustrated in Fig. 13. To determine the bisecting angle the outer members 22 and 21 of the lazy-tong construction are fitted on the corner or corner member designated 50 in Fig. 13, and when these members properly fit the corner or make the same angle as at 130

the side edges of the member 50, thence the instrument will be set in this position by tightening the set screw 16^a. The edge of the flange 14 and the adjacent edge of either 5 the arm 19 or arm 20 will thence form an angle equal to the bisecting angle desired, and the arm 19 or 20 will thence be in the proper position to mark the line of cut for a miter joint between two members which are to be 10 joined in such corner. Furthermore, the size of an angle of a corner can be determined by fitting the arms 21 and 22 on to the corner, as shown in Fig. 13, and thence setting the instrument whereupon the size of the angle 15 can be determined simply by multiplying by two the angle designated by the position of the indicator on scale 36.

Additionally, the instrument has a very 20 important use as a clinometer. In order that the instrument may be used for this purpose, it is provided with one or more spirit levels, which in this particular instrument when used for the purpose stated, have a novel 25 coöperation with several of the other parts. Preferably, we provide in the flange 14 two spirit levels 51 and 52 which are shown in Figs. 13 and 14. When it is desired to determine the inclination of any member, such 30 as the inclined member 53 of Fig. 14, the outer arm 21 of the lazy-tong construction is placed either on top or on the under side of the member, and thence by means of the spirit level or levels the base or body of the square can be made to assume a horizontal 35 position, whereupon the indicator will indicate directly on the scale 36 the inclination of the member 53. Without either the spirit level or the scale and indicator which are brought directly into use when the instrument 40 is used as a clinometer, it would have practically no value for this purpose. This is mentioned at this point to make clear the fact that the arm 21, spirit level and scale with the sliding indicator have a coöperating 45 action in the attainment of a very important result.

Additionally, the instrument is provided 50 with a sliding extension 55 which may be employed for a variety of purposes. This sliding extension 55 is in the form of a flat tongue or arm which normally lies in the slot or space between the top and bottom plates of the body or beam on the side of the interior rib 15 opposite to that which receives the lazy-tong marker support. This extension slide is provided with a central 55 groove 56, and extending into this groove is the end of a set screw 57 which permits the slide to move into a variety of positions, and at the same time retains the slide on the beam or body. As shown in Fig. 11, this 60 slide is provided with regular measuring graduations, and when the slide is extended its full length in a direction parallel to the body, these graduations constitute a continu-

ation of the graduations 13 along one margin or edge of the top plate 10. Preferably the base of the groove is provided at intervals with holes or openings 58 which may be and preferably are spaced an inch apart, 70 into which openings the end of the set screw 57 may be inserted to position the slide at any particular point.

The slide may be turned on the pivot screw 57 and by the latter may be clamped 75 at any desired angle, as shown, for example, by several dotted line positions in Fig. 11. In this manner the slide may be utilized as a bevel square. The slide may be swung around at right angles to the body or beam, 80 as shown in full lines in Fig. 11, in which event it serves as a tri-square, or as an adjustable T-square. When in this position at right angles to the body or beam, the edge of the slide bears firmly against a block or 85 abutment 58 (see particularly Fig. 3) which holds the slide at the right angle position.

When the slide is at the right angle position with respect to the beam or body, it 90 may be used to advantage as a plumb, in which event the spirit level or levels again have coöperating action.

From the above it will be observed that we have provided an instrument which can 95 be so compactly folded that it can be conveniently carried in a pocket, and although composed of relatively few parts, this device may be utilized for a great many measuring, gaging and marking purposes. Additionally, the instrument is extremely accurate and durable, none of the parts being liable to get out of order, assuming that the instrument is not subjected to unusual usage. 100

While we have shown one embodiment of 105 our invention, we do not desire to be confined to the exact details shown, and aim in our claims to cover all modifications which do not involve a departure from the spirit and scope of our invention. 110

Having thus described our invention, what we claim is:—

1. In a folding square, a beam or body, an extensible marker support comprising a plurality of arms pivotally connected in the form of a lazy-tong construction, the inner ends of two of the arms being connected to the beam, one pivotally connected at a fixed point, and the other having a sliding connection with the beam and adapted to travel 115 in a path in line with said fixed point, and another of said arms having a marking point located opposite said fixed pivoted point and movable in a line at right angles to the beam when the support is extended or collapsed, said beam being composed of upper and lower plates between which the support is received when collapsed. 125

2. In a folding square, a beam or body, an extensible member comprising a plurality of 130

pivotedly-connected arms in the form of a lazy-tong construction, the inner end of one of the arms being pivoted to the beam or body, and the inner end of another of said 5 arms having a sliding connection with said beam or body, a scale graduated to indicate angles which one of said arms may make with respect to an edge of said beam or body, an indicator coöperating with said 10 scale and operatively-connected with said extensible member, and a spirit level carried

by said beam or body to indicate the position of a part thereof with reference to the horizontal.

In testimony whereof, we hereunto affix 15 our signatures in the presence of two witnesses.

FITZ GERALD SHELBY.
PERRY OLMSTED.
